CLAIM

The ornamental design for an automobile armrest,
substantially as shown.

DESCRIPTION

FIG. 1 is a perspective view of an automobile armrest
showing the front, top and left side of my new design;
FIG. 2 is a top plan view thereof;
FIG. 3 is a front elevation view thereof;
FIG. 4 is a left side elevation view thereof;
FIG. 5 is a rear elevation view thereof; and
FIG. 6 is a bottom plan view thereof.
